UNITED STATES PATENT OFFICE

2,550,400

FLOOR DRAIN

Edward W. N. Boosey, Detroit, Mich.

Application April 19, 1946, Serial No. 663,581

4-Claims. (Cl. 210—56)

1

This invention relates to floor drains the object being to provide a new and improved floor drain which includes a chambered body having an inlet and an outlet chamber, an apertured depending plate separating the chambers, a cover member having an apertured portion through which fluid may discharge to the first chamber and including a depending flange spaced from the partition separating the chambers and a basket in the bottom of the inlet chamber into which solid matter carried by the inflowing liquid is deposited whereby fluid flowing through the outlet is practically freed of solid matter flowing to the sewer.

These and other features and objects of the invention are hereinafter more fully described and claimed and a device embodying my invention is shown in the accompanying drawing in which—

Fig. 1 is a plan view of the device.

Fig. 2 is a section taken on line 2—2 of Fig. 1.

In the preferred form of the invention in the drawings shown, the device comprises a body 1 having a flange 2 at its upper end providing a shoulder 3 on which a cover member 4 is supported. The said cover member has a short depending plate 5 having an aperture 6 therein and an additional depending plate 7 having transverse apertures 9 and 10 therein in vertically spaced relation. The plate 7 is in vertical alignment with the inner wall 11 of the chamber 12 and is spaced from its upper end defining the fluid passage 8 between chambers 12 and 18 as shown in Fig. 2. The cover member 4 has a series of apertures 13 and a series of apertures 14 therein through which sewage containing solid matter may pass and collect within basket 15.

The basket is provided with a bail having inner ends 16 and 17 extending through apertures provided therefore in the basket 15. By removal of the cover 4 the basket may be removed to dispose of the solid matter accumulating therein. The bottom wall of the chamber 18 is provided with an opening 19 which has an inwardly extending circular flange 20 to receive the inlet end of a trap 21 adapted to be connected at the discharge end 22 with a sewer.

By means of the said apertured plates 5 and 7, the rising liquid passes through the apertures in the plates to the outlet chamber 18 and the heavier particles of solid matter deposit in the removable basket 15.

Upon a flow of liquid into the chamber 12, the solid portions of matter are deposited in the basket and any floating particles at the surface of the water are discharged through the passage

8 and aperture 9 and thence to the sewer. If the inflowing liquid is greater in volume than the volume discharging through the passage 8 and aperture 9, the surface of the liquid and floating material thereon may pass through the said apertures 6 and 10 in the plates 5 and 7 to the sewer.

The plates 5 and 7 are preferably integral with the cover member whereby upon removal of the cover the plates are likewise removed thereby permitting access to the interior of the chamber 18. In the event the passageway between the plate 7 and the upwardly extended flange 20 becomes clogged, removal of the cover member permits removal of the accumulated solid matter. The inlet end 21a of the trap 21 is preferably internally threaded to receive a sealing plug (not here shown), which, when positioned therein, prevents backflow from the sewer.

The aperture 10 in the plate 7 permits seepage through the aperture 14 to the outlet chamber 18 in the event of accumulation of material to cover the lower end of the plate 5. Also in such case water flowing through apertures 13 also flows through the apertures 6 and 10 in the plates 5 and 7.

It is believed obvious from the foregoing description that removal of the cover member permits access to the interior of the drain and removal of the basket 15 and the removal of accumulated matter between the flange 7 and the flange 20. The plate 7, here shown as integral with the cover member, may be made integral with the body.

Having thus briefly described my invention, its utility and mode of operation, what I claim and desire to secure by Letter Patent of the United States is:

1. A floor drain comprising a body having inlet and outlet chambers, a cover on said body for said chambers, said cover having a depending plate separating said chambers, the lower end of said plate being spaced from the bottom of said outlet chamber defining a fluid passage between said chambers, said plate having an aperture adjacent its lower end, a second plate shorter than said first plate depending from said cover into said inlet chamber in parallel spaced relation to said first plate and having a transverse aperture therein, and a receptacle in the bottom of the inlet chamber the upper end of which is approximately in alignment with the bottom of said outlet chamber, said receptacle providing for the deposit of solid matter therein and permitting free flow of liquid to said outlet chamber.

2. A floor drain comprising a hollow body hav-

ing inlet and outlet chambers, a cover member on said body common to both said chambers, said cover member having apertures in that portion thereof covering the inlet chamber, said cover member including a depending plate separating the inlet chamber from the outlet chamber and terminating above the inner wall of the inlet chamber defining a fluid passage, an apertured depending plate upon the under side of the apertured portion of said cover member, being shorter than said first depending plate, and an outlet conduit connected with said outlet chamber.

3. A floor drain comprising a hollow body having inlet and outlet chambers, a cover member on said body common to both said chambers, the cover member having an integral depending plate terminating above and in vertical alignment with the inner wall of said inlet chamber defining a fluid passage between said chambers, there being transverse apertures in said depending plate, an apertured depending plate upon the under side of the apertured portion of said cover member, and a basket in the bottom of said inlet chamber.

4. A floor drain comprising a hollow body having an inlet chamber on one side and an outlet chamber of less depth than the inlet chamber on the other side, a cover member on said body for said chambers having an integral depending plate terminating above and aligned with the inner wall of the inlet chamber defining a fluid passage between said chambers, the cover member

having apertures in the portion thereof above the inlet chamber, the outlet chamber having a flanged opening in the bottom thereof, an outlet conduit extending into the said opening and terminating above the lower edge of said depending plate, the latter having a series of transverse apertures permitting seepage from the inlet chamber to the outlet chamber when the accumulated solid matter in the inlet chamber engages the lower edge of said depending plate closing off said fluid passage, and an apertured depending plate upon the under side of the apertured portion of said cover member, being shorter than said first depending plate.
